UNITED STATES PATENT OFFICE

DAVID PHILLIPS, OF DAYTONA BEACH, FLORIDA

ASTRONOMICAL DEVICE

Application filed May 26, 1930. Serial No. 455,737.

This invention relates to improvements in educational devices, and more especially in the astronomical device patented by David Phillips, June 28, 1927, 1,634,207, and it consists of the constructions, combinations and arrangements herein described and claimed.

An object of the invention is to improve the means whereby the figure herein identified as the moon and its shadow is made to preserve a true horizontal position during every portion of its rotation about the earth sphere.

A further object of the invention is to employ as a part of this means, a certain stationary sprocket in reference to which a crank arm carrying the moon figure is revoluble, the application of a chain to said sprocket as well as to a revoluble sprocket on the moon figure shaft not only being the means whereby the foregoing horizontal relationship is preserved, but also the means by which a perfectly smooth action is obtained.

Other objects and advantages will appear in the following specification, reference being had to the accompanying drawings in which

Figure 1 is a front elevation of an astronomical device somewhat on the order of that in the patent already mentioned,

Figure 2 is a vertical section taken on the line 2—2,

Figure 3 is a rear elevation of the device, parts being shown in section.

Figure 4 is a longitudinal section taken on line 4—4 of Figure 1.

A base member 10 has an upstanding panel 11 to which a central dial 12 is fixedly secured in concentric relationship to a ring 13. This ring is held in a stationary position both by means of a bracket 15 which is secured to the base 10, and by means of a brace 16 which extends to a point of attachment of the top of the panel 11 (Fig. 2). The annular slot 14 is traversible by a shaft

17 (Fig. 4) as well as a carried sleeve 18.

It is by these elements that the moon figure generally denoted 19 is carried. The moon figure comprises a sphere 20 which is secured to the shaft 17 in any approved way. The shaft 17 is fixedly secured to an arm 21 which

is capable of rotary motion in the operation of the device. The shaft 17 and sphere 20 move with the arm but are incapable of any relative movement whatsoever.

The moon figure 19 includes a cone 22 which is so situated as to represent its shadow. It is the principal purpose of the invention to maintain the shadow 22 in a true horizontal position while the annular slot 14 is traversed, and for this purpose the cone 22 is secured at 23 (Fig. 4) to the sleeve 18. This sleeve is capable of rotary motion in respect to the shaft 17, otherwise the desired horizontal position of the shadow or cone 22 could not be preserved.

A sprocket 24, secured to the sleeve 18 has a chain 25 applied thereto as shown in Figure 3. This chain also passes around a sprocket 26 (Fig. 2) which is herein known as the stationary sprocket. This sprocket is rendered stationary or stationary by virtue of its attachment at 27 to a stationary sleeve 28 that at one end has a flange 29, or its equivalent, by means of which attachment is made to the panel 11.

At its opposite or outer end the stationary sleeve 28 has secured thereto a cone 30 which, as in the instance of the moon figure 19, is intended to represent the shadow of the earth sphere 31. The earth sphere is capable of rotation by virtue of being attached to a central shaft 32, but the cone 30 remains immovable by virtue of its mounting on the sleeve 28.

The means by which motion is imparted both to the arm 21 and the shaft 32 comprises the following:—A pulley 33 and sprocket 34, each fixed on the shaft 32 (Fig. 2), have a drive belt 35 and a chain 36 respectively applied thereto. The chain 36 extends to a sprocket 37 which is mounted on one end of a counter shaft 38 that is supported by the panel 11. This counter shaft has another sprocket 39 (Fig. 3) to which as well as to a sprocket 40 a chain 41 is applied.

The sprocket 40 is part of a sleeve 42 which is revoluble upon the stationary sleeve 28. The sleeve 42 carries the arm 21 previously mentioned as well as the counter balancing arm 43 to which a weight 44 is applied. Thus far it will be understood that rotation of the

100

pulley 33 (Fig. 2) will simultaneously rotate the shaft 32 as well as the sleeve 42 thus causing revolution of the earth sphere 31 and rotary motion of the arm 21. However, the 5 rates of revolution are different, and in practice are accurately calculated by employing sprockets of various sizes as clearly indicated.

It may be here stated that in practice the sprocket and chain drives may be substituted 10 by gear drives. It is regarded as of little moment how the shaft 32 and sleeve 42 are driven so long as the required ratios are obtained, or in other words as long as the earth sphere 21 and moon figure 19 move at the 15 proper relative rates.

Reverting to the structural features in Figure 2, it is to be observed that the revoluble sleeve 42 is held in its place on the sleeve 28 by a collar 45 which is set on the sleeve 28. 20 The opposite end of the sleeve 42 abuts the hub of the static sprocket 26. The cone 30 (Fig. 1) to which reference has been made, is secured to the stationary sleeve 28 (Fig. 2) in any appropriate manner and is thus rendered stationary in relationship to the earth 25 sphere.

A recess 46 in back of the central dial 12 receives the flange 47 of a collar 48 which is also secured to the stationary sleeve 28. The 30 flange is secured to the dial, for example, by a screw or equivalent means 49, whereby the central dial is held in the stationary position previously spoken of.

The remaining structure is substantially 35 on the order of the disclosure in David Philip's Patent 1,634,207. For example, the ring 13 is provided with graduations 50 which represent the days of movement of the moon in its orbit or, in other words, the 40 space covered by the moon in one day. The central dial 12 has graduations 51 which represent the hours of a day. These graduations may be supplemented with any desired indicia, but since the instant invention is concerned chiefly with the means for keeping the 45 moon figure 19 in the desired horizontal position, this indicia is not required to be elaborated upon.

It will be apparent at once from the foregoing 50 description that the mechanical arrangement of the means for revolving the earth sphere 31 and causing the moon figure to traverse its orbit (Fig. 2) has the advantage of being completely concealed by the central dial 12 and ring 13. In this respect alone the instant device is an improvement on the foregoing patent in which the carrying element of the moon figure is in full view, thus detracting somewhat from the effectiveness 55 of the device as a demonstrator.

The operation will be readily understood. It has been pointed out that power applied 60 to the pulley 33 by means of the belt 35 (Fig. 2) causes simultaneous rotation of the shaft 32 and of the arm 21, the latter receiving its

motion through the driving means 34, 37, 39, 41 and 40.

The latter means is a sprocket integral 70 with the sleeve 42 that carries the arm (Fig. 2). It will be understood that as the arm 21 carries the moon figure 19 around there will be a continuous winding and unwinding of the chain 25 (Fig. 3) in reference to the stationary sprocket 26.

Thus action of the chain 25 causes a turning 75 of the sleeve 18 (Fig. 4) relatively to the shaft 17 which is fixed on the arm 21. The cone 22 representing the shadow of the moon, therefore, undergoes a continuous change in position in relationship to the shaft 17, but is made to maintain the identical horizontal 80 position in reference to the dial 12 and ring 13 which it traverses.

It has been pointed out that one of the specific purposes of the invention is to maintain 85 the horizontality of the moon shadow 22 in reference to the dial 12 and ring 13, it being assumed that the luminary which causes the casting of the shadow is located at a remote point at the right (Fig. 1). A secondary 90 purpose is to conceal the actuating mechanism so that only the essential elements of the device are visible.

While the construction and arrangement 95 of the improved astronomical device is that of a generally preferred form, obviously modifications and changes may be made without departing from the spirit of the invention or the scope of the claims.

I claim:—

1. An astronomical device comprising an earth sphere, a moon figure, cone representing the moon shadow, means for moving the moon figure in an orbital path around the earth sphere, and means for keeping the cone in a horizontal position during the orbital travel of the moon figure comprising a stationary sprocket, a chain, and driven means carrying said cone, said driven means being driven by the chain. 100

2. In an astronomical device, a revoluble arm, a sphere having a shaft fixed to the arm, a cone extending from the sphere representing its shadow, a sleeve carrying the cone and being mounted on the shaft, and means stationary in reference to the arm having a driving connection with the sleeve causing a continuous change of position of the cone in reference to the sphere during the 115 revolution of the arm. 120

3. In an astronomical device, a stationary sleeve having a sprocket attached thereto, an arm revolably mounted on the sleeve, a sphere having a shaft secured to the arm, a cone extending from the sphere and representing its shadow, a sleeve revoluble on the shaft and carrying a sprocket, the cone being rigidly connected to the sleeve and a chain connecting both sprockets causing a continuous 125 130

change of position of the cone in reference to the sphere during the revolution of the arm.

4. In an astronomical device, a stationary sleeve, a sphere having an attached shaft rev-
5 oluble in the sleeve, and a cone extending from the sphere and representing its shadow, said cone being attached rigidly to the sleeve hence stationary in respect to the sphere.

5. In an astronomical device, a stationary
10 sleeve, a revolute sleeve mounted thereon, an arm having an extension on each side of the revolute sleeve, a sphere having a shaft attached to one end of the arm, a cone extending from the sphere to represent its shadow,
15 means for both supporting the cone and having connection with the stationary sleeve for causing relative turning of the cone during revolution of the arm, and a counter weight on the opposite end of the arm balancing the
20 structure carried by the first end.
